UNITED STATES PATENT OFFICE

JOHN GRANTONIC, OF MINGO JUNCTION, OHIO

AMUSEMENT DEVICE

Application filed April 22, 1929. Serial No. 357,224.

The present invention relates to improvements in amusement devices and has reference more particularly to a game wherein a figure is normally hidden from view, means being provided which, when struck by a missile will effect the release of the object whereby to permit the latter to be moved into position where the same may be readily viewed.

Another important object of the invention 10 is to provide an amusement device of the above mentioned character that includes a means for returning the movable parts to their initial position whereby to reset the device for further use.

Another important object is to provide 15 an amusement device of the above mentioned character that includes a single means for resetting all of the projected figures to their lowered initial positions and this, without 20 affecting those figures already held in a lowered position out of view.

Another object is to provide an amusement device of the above mentioned character that includes a particular target structure for association with a pivoted trigger 25 whereby to disengage the same from the figure supporting member when the target is struck by a ball thrown by the player standing a suitable distance away from the target, additional means being provided for automatically projecting the figure and its carrying member upwardly to a position where 30 the same is readily and easily viewed.

A still further object is to provide an 35 amusement device of the above mentioned character which is simple in construction, inexpensive, strong and durable and further well adapted to the purpose for which it is designed.

Other objects of the invention will become 40 apparent as the nature of the invention proceeds and when taken in connection with the accompanying drawings.

In the accompanying drawings;

Figure 1 is a top plan view of the amusement device embodying my invention.

Figure 2 is a front view thereof.

Figure 3 is a vertical sectional view, taken approximately on the line 3—3 of Figure 4, looking in the direction of the arrows.

Figure 4 is a longitudinal vertical sectional view through the device showing the parts in their initial or normal position.

Figure 5 is a transverse section taken approximately on the line 5—5 of Figure 3, 55 looking downwardly.

Figure 6 is an enlarged detail of the target and trigger structure showing the manner in which the trigger secures the vertically movable figure supporting member in its 60 lowered position.

Figure 7 is a vertical sectional view, showing the position of the parts when the target has been struck by a ball and the trigger is released from the pin carried by the vertically movable figure supporting member, the latter being shown in its uppermost position for the purpose of displaying the figure.

Figure 8 is a detail sectional view through 70 the cylinder within which operates a counter-weight.

Figure 9 is a detail perspective view of the figure supporting member, forming a 75 salient part of the present invention.

Figure 10 is a detail of a modification of the means for resetting the movable parts to their initial positions, the means being electrically operated.

Figure 11 is a view looking at right angles 80 to Figure 10, for more clearly disclosing the relationship of the parts.

Figure 12 is a detail of the pitman that is eccentrically connected to the large spur gear, and

Figure 13 is a detail of the spring pressed 85 bearings for the stub shaft associated with one of the setting levers.

In the drawings, wherein for the purpose of illustration is shown the preferred embodiment of my invention the numeral 1 designates generally a partially enclosed structure which includes a front wall 2 disposed at a slight incline, a rear wall 3, a ceiling 4, and side walls 5.

The front wall terminates below the ceiling as clearly shown in Figure 4, and a woven wire mesh screen 6 is arranged between the forward edge of the ceiling 4 and the upper edge of the front wall 2. In addition, suit- 100

able scenery 7 is suspended from the ceiling 4 adjacent the rear wall 3, so as to be visible through the screen 6 as suggested very clearly in Figure 2.

5 A cushioning pad 8 is secured to the outer or front face of the front wall 2, in any appropriate manner and extending forwardly from the side walls 5 adjacent the ends of the cushioning pad 8 are the diverging wings 9.

10 A counter 10 is arranged a suitable distance in front of the structure 1 and this counter includes a tray 11, in the top thereof, in which balls are placed for use by the player.

15 A receptacle 12 is arranged below the tray 11, for receiving the balls that have been thrown by the player against the targets, which are to be presently described in detail. To this end, a ball return trough 13 extends from the front wall 2 to the counter 10 and is inclined inwardly toward the counter. Downwardly converging side walls 14 of canvas are associated with the trough 13 and a suitable frame structure shown generally at 15 is provided for supporting the ball return trough and the side walls as shown more clearly in Figure 2.

20 A bar extends horizontally across the rear face of the front wall 2 and extending through this bar 16 as well as through the front wall 2 and the cushioning pad 8 arranged against the front face thereof are the spaced sleeves 17, the same being disposed at a slight angle as more clearly shown in Figure 6 of the drawings.

25 Each sleeve is fixedly mounted and slidable through each sleeve is an elongated rod 18, the inner or rear end thereof being threaded as indicated at 19, while carried at the forward end of each rod 18 is the disc shaped target 20. An expansible coil spring 21 encircles the outer end portion of each rod for disposition between the forward end of the sleeve 17 and the target 20 for normally urging the rod 18 outwardly to space the target 20 with respect to the pad 8, as also clearly indicated in Figure 6 of the drawings.

30 A nut 22 is threaded on the threaded portion 19 of each rod 18 and cooperates with the inner or rear end of the respective sleeve 17 for adjusting the rod with respect to its sleeve, whereby to limit the outward sliding movement of the rod by the action of the expansible coil spring 21.

35 A series of spaced cross bars 23 extend between the front and rear walls 2 and 3 directly above the longitudinally extending bar 16 and pivotally mounted on one side edge of each cross bar 23 as at 24 is the vertically disposed trigger 25. A notch 26 is formed in the side edge of each trigger 25 adjacent the upper end thereof and the upper end of each trigger terminates in a nose 27.

40 A retractile coil spring 28 maintains the lower end of each pivoted trigger 25 in en-

gagement with the inner or rear end of the respective target carrying rod 18. There are as many triggers as there are target supporting rods and I do not wish to limit myself to the particular number of targets and triggers that may be employed in conjunction with the present amusement device.

45 Additional cross bars 29 extend between the front and rear walls 2 and 3 below the respective cross bars 23, and arranged through suitable registering openings formed in the upper and lower transverse cross bars are the sleeves 30. An elongated rod 31 that carries at its upper end a base or platform 32 is arranged for vertical slideable movement through each sleeve 30. A stop forming collar 33 is arranged on the intermediate portion of the rod 31 for limiting the upward sliding movement of said rod.

50 Each rod is formed with an opening 34 directly beneath the collar 33, a similar opening 35 being formed in the lower extremity of each rod 31, for a purpose to be presently described. An eye bolt 36 projects from the forward end of the block or platform 32 for cooperation with suitable guide rods 37 that extend between the top of the front wall 2 and the respective cross bars 23 to prevent rotation of the rods 31 and the blocks or platforms 32 carried by the upper ends thereof. A pin 38 extends laterally from one side edge of each block or platform 32 adjacent the forward end thereof for cooperation with the notch 26 of the respective pivoted trigger 25 as clearly shown in Figure 6.

55 Carried on the upper face of each block or platform 32 is a doll or other suitable figure denoted by the reference character 39. Normally the dolls or figures 39 are disposed below the upper edge of the front wall 2 so that the same are not visible through the opening afforded by the space between the upper edge of the front wall 2 and the ceiling 4, which space is covered by the wire mesh screen 6.

60 A board 40 extends horizontally across the upper edges of the forward end portions of the cross bars 23 to support the lamp sockets 41 in which are arranged electric lamps 42 provided for illuminating the scenery 7 and for casting a reflection upon the figures when the same are projected upwardly to a position for view.

65 A series of transversely disposed cross bars 43 extend between the front and rear walls of the structure 1, adjacent the bottom thereof and extending through the rear portion of each of the lower cross bars 43 is the threaded lower end 44 of a cylinder 45. Suitable nuts 46 are threaded on the threaded portion 44 of each cylinder 45 for engagement with the upper and lower faces of the respective cross bars 43, in a manner as more clearly disclosed in Figure 8 of the drawings. A cap 47 is removably secured on the upper end

of each cylinder and operable in each of the vertically disposed cylinders 45 is a counter-weight 48. A cable 49 is secured at its lower end to the respective counter-weight 48, said 5 cable being trained over a suitable pulley 50 that is suspended from a respective cross bar 29, the other end of the cable being secured to the apertured lower end 35 of the respective vertically movable rod 31 in the manner 10 as more clearly disclosed in Figure 3 of the drawings.

A longitudinal bar 51 extends across the upper edges of the lower cross bars 43 and is secured to the rear side of the front wall 2 in 15 any appropriate manner. Hingedly secured to the upper edge of this bar 51 is a vertically swinging bar 52, that has attached thereto the vertically extending levers 53, for swinging movement with the bar 52. An eye bolt 54 is 20 attached to the rear face of the upper end portion of each lever 53, and suitable cables 55 operatively connect the eye bolt 54 with a respective rod 31 at the aperture 34, in the manner as clearly shown in Figure 3 and for 25 a purpose to be presently apparent.

A main rope or cable 56 is secured at one end to the intermediate lever or arm 53, and this cable is trained over a suitable pulley 57 arranged in the bottom rear portion of the 30 structure 1, and the cable extends through a suitable opening provided therefor in the front wall 2 and through the lower portion of the counter 10, and an actuating ring 58 is attached to the free end of this cable as clearly 35 shown in Figure 4.

As shown very clearly in Figure 3 there is a certain amount of slack in the cables 55 that connect the intermediate portions of the vertical movable rods 31 with the respective 40 levers or arms 53.

The operation of my improved amusement device may be briefly stated as follows. Normally the parts are arranged as shown in Figure 4 and it will be observed that the triggers 45 25 cooperate with the pins 38 to secure the vertically movable rods 31 and the figures 39 carried on the platforms 32 in a lowered position so that the figures are concealed out of view. When in this position, the counter- 50 weights 48 in the various cylinders 45 are disposed in their uppermost positions as shown in Figure 8.

The player aims at any one of the targets 20 and if one of the targets is struck with a ball, this particular target will move inwardly 55 against the tension of the coil spring 21 actuating the rod 18 which, in turn, will operate its respective trigger to disengage the notch 26 from the pin 38 and simultaneously the 60 weight 48 will travel downwardly in its cylinder 45, exerting a pull on the cable 49, in such a manner as to move the rod 31 upwardly, whereby to cause the figure 39 to be moved to position above the upper edge of the front 65 wall, where the same will be in view.

By striking any one of the other targets, the figure associated with the vertically movable rod controlled by that particular target will be raised to its uppermost position.

The balls striking the pad 8 will be returned to the counter by reason of the trough 13 and the receptacle 12 and the balls may be taken out of the receptacle 12 and placed in the tray 11, where the same are easily accessible to the player or players.

For resetting the parts so as to permit the exposed figures to be returned to their initial concealed positions, a pull on the ring 58 causes the cable 56 to be actuated and this cable will, in turn, swing the pivoted bar 52 and all of the arms or levers 53 carried thereby downwardly and this movement will result in the cables 55 being pulled downwardly to move the rods 31 downwardly until the pin 38 rides over the nose 27 of the respective trigger and engages behind the notch 26 where the movable rod 31 is locked in its lowered position.

It is to be understood that should only one or two of the various rods be raised to expose the figures carried thereby the resetting of these two particular rods will not interfere or release the other rods that have not been released and moved upwardly.

The pull rope 56 will permit the simultaneous resetting of all of the released figure supporting rods so that the amusement device will be in position for further use. This will obviate the further necessity of having to employ a number of attendants in conjunction with the amusement device, it being necessary for only one attendant to take care of the operation of the present invention.

In Figure 10 of the drawings, I have shown a modification of the resetting mechanism wherein the same is controlled by an electric motor. To this end, a small electric motor 59 of any conventional construction is arranged within the lower rear portion of the housing or structure 1 and a relatively small driving gear 60 is secured on the outer end of the drive shaft of this motor.

This driving pinion 60 meshes with a relatively large spur gear 61 that is mounted on a stub shaft 62.

A connecting rod 63 is adjustably secured at its lower end in a socket member 64, the latter being eccentrically connected to the driven gear 61, as at 65', with reference more particularly to Figure 12.

Cooperating with the upper end of the connecting rod 63 is a sectional frame 65, that includes a pair of complementary U-shaped sections having laterally extending ears at the free ends of the arms thereof through which is disposed appropriate fastening means.

A bracket 66 is secured on the upper end of one of the levers 53 and extending from this bracket is a pin 67 that is disposed

through the section frame 65 and complementary spring pressed bearings 68 engage the opposite side of the pin 67, the bearings being mounted in the frame 65. A nut 69 is removably secured on the outer end of the pin 67 to prevent displacement of the frame and the bearings 68 from engagement with the pin 67.

A small bell 70 is provided for the purpose of signalling the attendant when the connecting rod passes over dead center, which indicates that the dolls are in their lowered normal position, a trip 71 being associated with the pivoted striker of the bell to actuate the same, the trip being disposed within the path of movement of the element 64 carried by the lower end of the connecting rod 63.

A hook 72 may be provided for attaching one end of the pull cable 56 thereto when the motor is employed for resetting the movable parts of the device and should the motor fail, the connecting rod is disconnected from the gear 61 and also from the upper end of the lever 53 and the cable is then attached to the upper end of the lever whereby the parts may be reset by manually controlled means.

It will thus be seen from the foregoing description that I have provided an amusement device for use in amusement parks, coliseums, pleasure resorts or wherever it is desired to set up the amusement device, the same affording amusement to the players as well as requiring skill on the part of the players to strike the target, the object of the game being to project as many dolls or figures upwardly to view as is possible.

A structure of this character may be readily and easily assembled and access to the parts may be had whenever necessary.

Further, an amusement device of this character will, at all times, be positive and efficient in its operation as well as strong and durable.

While I have shown the preferred embodiment of my invention, it is to be understood that various changes in the size, shape and arrangement of parts may be resorted to, without departing from the spirit of the invention or the scope of the appended claim.

I claim:

In an amusement device, the combination of a housing structure, a vertically movable member mounted in said structure, a pivoted trigger, means carried by the vertically movable member for cooperation with the trigger to lock said member in lowered position, weight controlled means operatively connected with said vertically movable member for moving said vertically movable member upwardly when the trigger is released, a sleeve extending through the forward wall of said structure, a target carrying rod slidable through said sleeve, said rod having the inner end thereof in engagement with the free end of the trigger, means normally urging

said rod out of engagement with said trigger, means for varying the required distance of travel of the rod to engage said trigger, and means for lowering the vertically movable member, comprising a lever arranged for vertical swinging movement within the housing structure, a cable connecting the upper end of the lever with the vertically movable member, and means connected to said lever for swinging the same in one direction to retract the vertically movable member.

In testimony whereof I affix my signature.

JOHN GRANTONIC.
